IMAGE FORMING APPARATUS

BACKGROUND OF THE INVENTION

Field of the Invention

The present invention relates to an image forming apparatus using an electrophotographic system.

Description of the Related Art

In image forming apparatuses using an electrophotographic system such as copiers, printers, facsimile machines, and multifunction peripherals including copiers, printers, and facsimile machines, it has been known to use a process cartridge system in which photosensitive drums and processing means acting on the photosensitive drums are unitized as integral cartridges and made attachable/detachable to/from apparatus bodies. In the image forming step of an image forming apparatus, light such as laser light, LED light, and lamp light corresponding to image information is irradiated onto a photosensitive drum to form an electrostatic latent image thereon. Then, the electrostatic latent image is developed by a developing apparatus, and a developer image formed on the photosensitive drum is transferred onto a recording material to form an image thereon. In the above step, when attached to an apparatus body, a cartridge (unit) needs to expose its position at which the photosensitive drum opposes the recording material and its portion at which the photosensitive drum opposes body-side processing means acting on the photosensitive drum. In the replacement of the cartridge, the cartridge needs to be inserted so as not to contact the apparatus body to prevent damage on the surface of the photosensitive drum.

In view of the above problems, there has been proposed, as a method for inserting a cartridge, a configuration in which a rib serving as an inserting/extrating guide is provided on a door that opens/closes the opening portion of an image forming apparatus for replacement and the cartridge is mounted on the rib to be attached (Japanese Patent No. 5787490). Besides, there has been proposed a configuration in which a protection cover removable in a longitudinal direction is provided on a cartridge, a convex portion provided at the tip lower portion in the inserting direction of the protection cover is fitted in the concave portion of an image forming apparatus body, and the cartridge is guided in a state of being attached (Japanese Patent No. 3535604).

However, in the configuration in which the cartridge is attached in a state of being mounted on the rib, the height of the cartridge with respect to an apparatus body is made substantially the same between a state in which the cartridge is attached inside the image forming apparatus and a state in which the cartridge is mounted on the rib. Accordingly, in a configuration in which a photosensitive drum is exposed to the upper side of the cartridge, there is a likelihood that the cartridge contacts the apparatus body and damages the surface of the photosensitive drum when the cartridge is isolated from the rib.

Further, in the configuration in which the cartridge is guided by the protection cover to be attached, there is a concern that the function of guiding the cartridge is lost when a user erroneously removes the protection cover before attaching the cartridge to the apparatus body.

It is an object of the present invention to provide a technology capable of preventing the occurrence of damage or the like on members constituting a unit in a configuration in which the unit is made attachable/detachable to/from an image forming apparatus body.

SUMMARY OF THE INVENTION

In order to achieve the above object, an embodiment of the present invention provides an image forming apparatus

2

including: an apparatus body; a first unit and a second unit that are configured to be attachable/detachable to/from the apparatus body; an opening/closing member that opens/closes space which is provided in the apparatus body and in which the first unit and the second unit are accommodated; a first guide portion that is provided in the apparatus body and guides the first unit in the space; a second guide portion that is provided in the apparatus body and guides the second unit in the space; and a slope member that is capable of guiding the first unit to the first guide portion at a position higher than a position of the second guide portion in a height direction orthogonal to an inserting/extrating direction of the space when the opening/closing member is put in an open position, the slope member being coupled between the apparatus body and the opening/closing member so as to be positioned in the space when the opening/closing member is put in a closed position to close the space.

In addition, in order to achieve the object, an embodiment of the present invention provides an image forming apparatus including: an apparatus body; a first unit that is configured to be attachable/detachable to/from the apparatus body; a second unit that is configured to be attachable/detachable to/from the apparatus body; a first guide portion that is provided in the apparatus body and guides the first unit to a first attachment position of the apparatus body; and a second guide portion that is provided in the apparatus body and guides the second unit to a second attachment position of the apparatus body, wherein the first guide portion and the second guide portion are different in height in a vertical direction of the apparatus body.

Further features of the present invention will become apparent from the following description of exemplary embodiments (with reference to the attached drawings).

BRIEF DESCRIPTION OF THE DRAWINGS

FIGS. 1A and 1B are schematic perspective views of an image forming apparatus according to a first embodiment of the present invention. FIG. 1A shows the image forming apparatus with an access door closed. FIG. 1B shows the image forming apparatus with the access door open.

FIG. 2 is a schematic cross-sectional view of the image forming apparatus according to the first embodiment of the present invention.

FIGS. 3A to 3D are schematic perspective views of a process cartridge according to the first embodiment of the present invention. FIG. 3A is a bottom side perspective view of the process cartridge. FIG. 3B is an upper side perspective view of the process cartridge. FIG. 3C is a perspective view of a development unit of the process cartridge, and FIG. 3D is a perspective view of a drum unit of the process cartridge.

FIG. 4 is a block diagram showing the configuration of the control unit of the image forming apparatus according to the first embodiment of the present invention.

FIGS. 5A to 5D are schematic views for describing the configuration of contact/separation means according to the first embodiment of the present invention. FIG. 5A is a perspective view of the driving unit of the contact/separation means, and FIG. 5B is a detailed perspective view of the driving unit of the contact/separation means shown in FIG. 5A. FIG. 5C is a schematic cross-sectional view of a process cartridge and the contact/separation means during development contact, and FIG. 5D is a schematic cross-sectional view of the process cartridge and the contact/separation means during development separation.

FIGS. 6A to 6D are schematic views for describing the configuration of the contact/separation means according to

the first embodiment of the present invention. FIG. 6A is a perspective view showing the biasing configuration of one station during development contact, and FIG. 6B is a perspective view of the biasing configuration shown in FIG. 6A in which a slider is removed for illustrative purposes. FIG. 6C is a perspective view of the apparatus shown in FIG. 6A showing the back sides of components on the rear side. FIG. 6D is a perspective view of the apparatus shown in FIG. 6A showing a configuration during development separation as opposed to the development contact shown in FIG. 6A.

FIGS. 7A to 7D are schematic views for describing the configuration of the contact/separation means according to the first embodiment of the present invention. FIG. 7A is a partially enlarged view of the apparatus when seen from the front side during development contact, and FIG. 7B is a partially enlarged view of FIG. 7A in which the relationship between the contact/separation means and a rib of the development unit is shown from the upper side of the apparatus. FIG. 7C is a partially enlarged view of the apparatus when seen from the front side during development separation, and FIG. 7D is a partially enlarged view of FIG. 7A in which the relationship between the contact/separation means and a rib of the development unit is shown from the upper side of the apparatus.

FIGS. 8A and 8B are schematic views for describing the opening/closing operation of an access door according to the first embodiment of the present invention. FIG. 8A is a partially enlarged cross-sectional view of the apparatus when seen from the right side, showing a state in which the access door is in a closed position. FIG. 8B is the view shown in FIG. 8A showing a state in which the access door is in an open position.

FIGS. 9A and 9B are schematic views for describing the opening/closing operation of the access door according to the first embodiment of the present invention. FIG. 9A is an enlarged view of a front side of a K-station showing the access door closed. FIG. 9B is the enlarged view of the K-station shown in FIG. 9A shown with the access door open. FIG. 9C is a partially enlarged view of a shape in the vicinity of a drum guide portion.

FIGS. 10A and 10B are schematic views for describing the relationship between a guide rail and the access door according to the first embodiment of the present invention. FIG. 10A shows a state in which the access door is open, and FIG. 10B shows a state in which the access door is closed.

FIG. 11 is a perspective view showing the configurations of the guide rail and a shaft or the like operating with the access door according to the first embodiment of the present invention.

FIGS. 12A and 12B are partially cross-sectional views for describing the configuration of a slope member according to the first embodiment of the present invention. FIG. 12A shows a state in which the access door is closed, and FIG. 12B shows a state in which the access door is open.

FIG. 13 is a perspective view showing the configurations of a guide rail and a shaft or the like operating with an access door according to a second embodiment of the present invention.

FIG. 14 is a schematic perspective view of an image forming apparatus according to the second embodiment of the present invention.

DESCRIPTION OF THE EMBODIMENTS

Hereinafter, a description will be given, with reference to the drawings, of embodiments (examples) of the present invention. However, the sizes, materials, shapes, their rela-

tive arrangements, or the like of constituents described in the embodiments may be appropriately changed according to the configurations, various conditions, or the like of apparatuses to which the invention is applied. Therefore, the sizes, materials, shapes, their relative arrangements, or the like of the constituents described in the embodiments do not intend to limit the scope of the invention to the following embodiments.

First Embodiment

10 Examples of an image forming apparatus to which the present invention is applicable include a copier, a printer, a facsimile machine, a multifunction peripheral including a copier, a printer, and a facsimile machine, or the like that forms an image on a recording material using an electro- 15 photographic system. Here, a description will be given of a case in which the present invention is applied to a color laser printer. An image forming apparatus according to this embodiment is a full color laser beam printer of four colors using an electrophotographic process, and forms a color 20 image on a recording material such as a paper. Further, the image forming apparatus is a process cartridge attachable/detachable type in which first to fourth (four) process cartridges are detachably attached to an image forming apparatus body to be used.

25 Here, in the image forming apparatus, a front side or a near side indicates a side on which an access door 101 is disposed. A rear side or a back side indicates a side opposite to the front side or the near side. A front-back direction indicates a direction from the rear side to the front side (a forward direction or a front direction) and its opposite direction (a backward direction or a rear direction). Right and left sides indicate right and left sides when the image forming apparatus is seen from the front side. A right-left direction indicates a direction from the right side to the left side (left direction) and its opposite direction (right direction). The front-back direction and the right-left direction indicate directions parallel to a horizontal direction, and a height direction indicates a vertical direction, i.e., a direction orthogonal to the front-back direction and the right-left direction. 30 Further, the image forming apparatus body indicates a constituent part of the image forming apparatus other than the process cartridges. Further, with respect to the process cartridges or their constituent members or constituent members on the side of the apparatus body, a longitudinal direction indicates the axis direction of electrophotographic photosensitive drums 1 serving as image bearing members or a direction parallel to the axis direction.

Image Forming Apparatus

FIGS. 1A and 1B are schematic perspective views of a printer 100 serving as an image forming apparatus to which process cartridges 7 (cartridges) are attachable/detachable to/from the image forming apparatus body (apparatus body). FIG. 1A is a view in a state in which the access door 101 for opening/closing an opening portion provided in the apparatus body to replace the cartridges 7 is closed. FIG. 1B is a view in a state in which the access door 101 is open, and the cartridges 7 may be extracted in the front direction of the apparatus when the access door 101 is open.

FIG. 2 is a schematic cross-sectional view of the printer 100 when seen from the front side. At the bottom of the printer 100, a cassette 11 is accommodated so as to be capable of being extracted. Transfer materials S serving as recording materials are accommodated in the cassette 11 in a stacked state, and separated one by one to be fed. The printer 100 has the cartridges 7 (7a, 7b, 7c, 7d) corresponding to the respective colors of yellow (Y), magenta (M), cyan (C), and black (K) as image forming means provided

side by side in a line. Each of the cartridges 7 is constituted by the two bodies of a development unit 4 (4a, 4b, 4c, 4d) and a drum unit (cleaner unit) 5 (5a, 5b, 5c, 5d) having a photosensitive drum. In general, toner may be quickly exhausted or photosensitive drums may be quickly exhausted depending on user's printing contents. That is, a timing at which the replenishment of toner (the replacement of development units) is needed does not necessarily match a timing at which the replacement of photosensitive drums (the replacement of drum units) is needed. In the embodiment, the cartridge 7 is constituted by the two bodies, i.e., the development unit 4 and the drum unit 5 are separately replaceable at a second attachment position and a first attachment position, respectively. Thus, it becomes possible to reduce printing costs and save resources from a user's point of view.

In the cartridge 7, the drum unit 5 has a photosensitive drum 1 (1a, 1b, 1c, 1d) serving as an image bearing member and a charging apparatus 2 (2a, 2b, 2c, 2d) that uniformly negatively charges the surface of the photosensitive drum 1. Further, the drum unit 5 has a cleaning blade 8 (8a, 8b, 8c, 8d) that removes residual toner on the photosensitive drum 1 after the transfer of a toner image and a toner container in which untransferred toner is accommodated.

In the development unit 4, a development roller (24a, 24b, 24c, 24d) serving as a developer bearing member and a developer coating roller 25 (25a, 25b, 25c, 25d) are rotatably supported by a frame body serving also as a toner accommodating container. The development roller 24 plays a role in attaching toner to an electrostatic latent image formed on the surface of the photosensitive drum 1 and developing the resultant image as a toner image (developer image). The development roller 24 is biased so as to be pressed against the surface of the photosensitive drum 1 at the contact position between the development roller 24 and the photosensitive drum 1 to attach the toner.

Here, in the present application specification, a contact position indicates a development position at which it is possible to attach toner to an electrostatic latent image on the photosensitive drum 1 to form a toner image, and indicates a position at which the development roller 24 contacts the photosensitive drum 1 or a position at which the development roller 24 comes close to the photosensitive drum 1. That is, the development roller 24 may not contact the photosensitive drum 1 so long as the contact position is a position at which toner is attached to an electrostatic latent image on the photosensitive drum 1 to form a toner image (in this case, the position is also called the contact position for the sake of convenience).

FIGS. 3A to 3D are schematic perspective views of the process cartridge 7 having the two bodies of the development unit 4 and the drum unit 5 in the embodiment. FIGS. 3A and 3B are views showing a state in which the development unit 4 and the drum unit 5 are arranged so as to act on each other to form an image as in image formation. FIG. 3C is a perspective view of the development unit 4, and FIG. 3D is a perspective view of the drum unit 5. The frame body of the development unit 4 is roughly constituted by a development frame 4f and a development container 4g, and the development frame 4f and the development container 4g are configured to be capable of swinging each other with a pin 27 as a swinging center. Thus, the development roller 24 is configured to be capable of contacting and separating from the photosensitive drum 1 (the development roller 24 is movable between a contact position and a separating position). The development unit 4 and the drum unit 5 are provided with handle portions 4j and 5e, respectively.

With this configuration, the development roller 24 is caused to contact the photosensitive drum 1 in synchronization with a timing at which toner is attached to an electrostatic latent image formed on the photosensitive drum 1 to be developed (contact state). In a period other than the timing, the development roller 24 is caused to separate from the photosensitive drum 1 to a greater extent (standby state), whereby the service lives of the development roller 24 and the photosensitive drum 1 are extended. A scanner unit 3 that irradiates a laser beam based on image information to form an electrostatic latent image on the photosensitive drum 1 is provided beneath the process cartridge 7, and an intermediate transfer unit 12 is provided on the process cartridge 7.

The intermediate transfer unit 12 has primary transfer rollers 12a, 12b, 12c, and 12d, an endless cylindrical intermediate transfer belt 12e, a driving roller 12f, a tension roller 12g, and a cleaning apparatus 22 that removes toner on the intermediate transfer belt 12e. The cleaning apparatus 22 is arranged on the upstream side of a primary transfer part 15 formed by the photosensitive drum 1a and a primary transfer roller 12a in the movement direction of the intermediate transfer belt 12e (in an arrow E direction in FIG. 2). In addition, the cleaning apparatus 22 is arranged on the downstream side of a secondary transfer part 15 formed by a driving roller 12f and a secondary transfer roller 16.

Moreover, the cleaning apparatus 22 is positioned and held by the shaft of the tension roller 12g, and configured to follow a change in the position of the tension roller 12g. Further, since the intermediate transfer belt 12e and the cleaning apparatus 22 are consumable items, the intermediate transfer unit 12 integrated with the cleaning apparatus 22 is made attachable/detachable to/from the apparatus body. Further, untransferred toner on the intermediate transfer belt 12e collected by the cleaning apparatus 22 is accumulated in a toner collecting container 26 arranged inside the printer 100.

When the driving roller 12f is rotationally driven by a driving source such as a motor (not shown), the intermediate transfer belt 12e rotates at a prescribe speed in an arrow X direction in FIG. 2. In primary transfer, a positive bias voltage is applied to the primary transfer rollers 12a, 12b, 12c, and 12d and a potential difference with the surfaces of the negatively-charged photosensitive drums 1 is used, whereby toner is transferred from the photosensitive drums 1 onto the intermediate transfer belt 12e (primary transfer).

At respective primary transfer parts formed by the primary transfer rollers 12a, 12b, 12c, and 12d and the photosensitive drums 1 in the respective image forming stations of the colors Y, M, C, and K, toner images on the photosensitive drums 1 are primarily transferred onto the intermediate transfer belt 12e in a stacked state. The toner images transferred onto the intermediate transfer belt 12e are transferred onto the transfer materials S at the secondary transfer part 15 formed by the driving roller 12f and the secondary transfer roller 16. After that, the transfer materials S pass through a fixing apparatus 14 that fixes a transfer image and then conveyed to a pair of discharging rollers 20 to be discharged to a transfer material stacking portion.

Here, a feeding apparatus 13 has a sheet feeding roller 9 that feeds the transfer materials S from the sheet feeding cassette 11 in which the transfer materials S are accommodated and a pair of conveyance rollers 10 that conveys the fed transfer materials S. The transfer materials S accommodated in the sheet feeding cassette 11 are brought into contact with the sheet feeding roller 9 by pressurizing, separated one by one by a separation pad 23 (friction piece separation method) and conveyed. Then, the transfer mate-

rials S conveyed by the feeding apparatus 13 are conveyed to the secondary transfer part 15 by a pair of resist rollers 17.

A fixing apparatus 14 applies heat and pressure to an image formed on the transfer materials S to be fixed thereon. Reference symbol 14a indicates a cylindrical fixing belt, and is guided by a guide member 14c to which heating means such as a heater is bonded. Reference symbol 14b indicates an elastic pressure roller, and the elastic pressure roller sandwiches the fixing belt 14a and forms a fixing nip portion N having a prescribed width at a prescribed pressure welding force with the guide member 14c.

Further, as will be described later, the printer 100 serving as an image forming apparatus has a control unit 200 that controls the image forming operation of the printer 100.

Control Unit

A description will be given, with reference to FIG. 4, of the control unit 200 that controls the image forming operation of the printer 100. FIG. 4 is a block diagram showing the configuration of the control unit 200 of the printer 100 serving as the image forming apparatus according to the embodiment. The printer 100 has the control unit 200 on which an electric circuit that controls the apparatus is mounted, and a CPU 40 is mounted on the control unit 200. The CPU 40 has a driving control unit 50 that conveys the transfer materials S and controls a driving source such as the process cartridge 7, a high-pressure control unit 41 that controls image formation, a contact/separation control unit 45 that controls the contact/separation of the development roller 24, or the like, and collectively controls the operation of the image forming apparatus.

The driving control unit 50 controls a photosensitive drum driving unit 51, an intermediate transfer belt driving unit 52, and a primary transfer mechanism driving unit 53 as driving control during image formation. The high-pressure control unit 41 controls a charging bias generation unit 42 that generates a voltage needed for image formation, a development bias generation unit 43, and a transfer bias generation unit 44. In addition, the control unit 200 has a motor drive IC (motor driving unit) 47 that controls the driving of a contact/separation motor (motor) 90 (see FIGS. 5A to 5D) of a development contact/separation mechanism that will be described later. Further, the excitation of the motor 90 is switched when the CPU 40 transmits a pulse signal (two-phase excitation is employed as an excitation system in the embodiment) to the motor drive IC 47.

The motor drive IC 47 having received a pulse signal controls the direction of a current flowing through the coil of the motor 90 corresponding to the pulse signal. On this occasion, a rotor magnet is structured to rotate with the inversion of a filed pole in the motor 90. Note that the rotation speed of the motor 90 depends on the frequency (hereinafter defined as the driving frequency) of the pulse signal transmitted from the CPU 40. The higher the driving frequency, the shorter the inversion cycle of the field pole in the motor 90 becomes and the faster the rotation speed of the motor 90 becomes.

The contact/separation control unit 45 that controls the timing of contact/separation or the like controls the pulse control unit 46 to control the motor 90, and a pulse signal generated by the pulse control unit 46 is transmitted to the motor driving unit (motor drive IC) 47. Further, the signal of a photo interrupter 49 serving as a position detection sensor that will be described later is transmitted to the driving timing control unit 48 and used to control contact/separation. In the embodiment, contact/separation means (FIGS. 5A to 5D to FIGS. 7A to 7D) is used in a transition from development separation to development contact.

Contact/Separation Means

A description will be given, with reference to FIGS. 5A to 5D to FIGS. 7A to 7D, of the contact/separation means using a transition in which the photosensitive drum 1 and the development roller 24 change from a development contact state to a development separation state as an example. The outline of the transition is as follows. In other words, a first cam 80 rotates about a rotation axis extending in the horizontal direction with the rotation of the motor 90 that drives the contact/separation means. Here, as a link mechanism that interlocks along a horizontal surface (link mechanism constituted by a plurality of members, each of which moves parallel to the horizontal surface), a lever 34, a slider 35, and a pressure spring 32 that biases the development roller 24 to the photosensitive drum 1 are provided. The lever 34 rotates about a rotation axis perpendicular to the horizontal surface, and the slider 35 and the pressure spring 32 are displaced in a direction parallel to the rotation axis of the first cam 80 (in the axis direction of the photosensitive drum 1). Further, with the rotation of a movement member 31 that rotates with the displacement of the slider 35, a rib 31f of the movement member 31 separates from a rib 4e of the development unit 4 (FIG. 5D). Thus, the photosensitive drum 1 and the development roller 24 change from the development contact state to the development separation state.

More specifically, as shown in FIG. 5A, the lever 34 first swings as indicated by an arrow F in FIG. 7D when the cam radius of a first cam 80 (80a, 80b, 80c, 80d) increases with rotation. Then, the slider 35 linearly moves from the front of the apparatus in the rear direction as indicated by an arrow H. Two bended portions 35j exist at the contact parts between the pressure spring 32 and the slider 35, and are allowed to contact a rib 31h of the movement member 31 (as indicated by the partially enlarged view of FIG. 7D). Therefore, when the slider 35 moves by a constant amount or more, the movement member 31 is caused by the slider 35 to start rotating as indicated by an arrow R in FIG. 7D. Next, the pressure spring 32 is gradually compressed. Then, a rib 31g of the movement member 31 moves the rib 4e of the development unit 4 from the left side to the right side of the apparatus (as indicated by an arrow J in FIG. 7D).

Next, a description will be given in detail of the contact/separation means for each of FIGS. 5A to 5D, FIGS. 6A to 6D, and FIGS. 7A to 7D.

1) About FIGS. 5A to 5D

FIG. 5A is a perspective view of the driving unit of the contact/separation means, and FIG. 5B is a partially perspective view around the photo interrupter 49 of the driving unit of the contact/separation means. Further, FIG. 5C is a schematic cross-sectional view of the process cartridge and the contact/separation means during development contact, and FIG. 5D is a schematic cross-sectional view thereof during development separation.

A stepping motor is used as the motor 90 serving as a driving source that switches the positions (the contact position and the separation position) of the development roller 24 with respect to the photosensitive drum 1, and is connected to a driving switching shaft (shaft) 95 via gears 91 and 92.

The shaft 95 is provided with a worm gear 93 (93a, 93b, 93c, 93d) that drives a cam gear 94 (94a, 94b, 94c, 94d) of each color. When the shaft 95 is rotated by the rotation of the motor 90, the cam gear 94 is rotated to change the rotation phase of a first cam 80 (80a, 80b, 80c, 80d). The first cam 80 is capable of restricting the positions of the development unit 4 and the development roller 24 via the contact/

separation means shown in FIGS. 6A to 6D that will be described later, and presses the rib 4e of the development unit 4 to switch the contact/separation of the photosensitive drum 1 and the development roller 24.

Thus, as shown in FIG. 5A, the shaft 95 and the first cam 80 (80a, 80b, 80c, 80d) are rotationally driven by the single motor 90 to make it possible to change the positions (the contact position and the separation position) of the development roller 24 with respect to the photosensitive drum 1. Further, as shown in FIGS. 5C and 5D, the development unit 4 makes it possible to rotate the development container 4g about the swinging center pin 27 with respect to the development frame 4f while rotatably supporting the development roller 24. Thus, the development roller 24 is biased in a clockwise direction (in a direction in which the development roller 24 contacts the first cam 80) with respect to the photosensitive drum 1 by the pressure spring 32 (FIGS. 6A to 6D) serving as biasing means.

2) About FIGS. 6A to 6D

FIGS. 6A to 6D are perspective views of the configuration of the contact/separation means that biases the process cartridge 7. FIG. 6A is a perspective view showing the biasing configuration of one station during development contact, and FIG. 6B is a view in which the slider 35 is removed from FIG. 6A for illustrative purposes. Further, FIG. 6C is a view showing the back sides of components on the rear side of the apparatus shown in FIG. 6A, and FIG. 6D is a view showing a configuration during development separation as opposed to the development contact shown in FIG. 6A.

In FIGS. 6A to 6C, a lever 34 that follows the first cam 80 exists. The lever 34 has a boss portion 34e, and the boss portion 34e is rotatably held by a hole (not shown) provided in a frame 102 (FIG. 2) of the apparatus body. In addition, the lever 34 has another boss portion 34f (FIG. 6B), and the boss portion 34f is fitted in an oval hole 35h (FIG. 6A) of the slider 35.

As shown in FIGS. 6A and 6D, the slider 35 is linearly slidably held in the directions of the front and rear sides of the apparatus by slider guides 28 and 29 (FIG. 6B) fixed to the frame 102. The slider guides 28 and 29 are provided with pins 30 at two places, and the pins 30 prevent the slider 35 from coming off in the upper direction of the apparatus.

Further, as shown in FIG. 6B, a movement member 31, the pressure spring (compression spring) 32, and a spring seat 33 are arranged at two places in the directions of the front and rear sides of the apparatus. The movement member 31 is provided with a boss portion 31e, and the boss portion 31e is rotatable with respect to the frame 102 like the lever 34. The spring seat 33 is fixed to the frame 102, and the pressure spring 32 is attached to the apparatus body between the movement member 31 and the spring seat 33.

In the embodiment, the lever 34 rotates with the rotation of the first cam 80 from a state shown in FIG. 6A, and the slider 35 moves from the front side to the rear side of the apparatus by an amount L (FIG. 6D). At this time, the movement member 31 rotates by an angle θ shown in FIG. 6D about the boss portion 31e with the movement of the slider 35, whereby it becomes possible to change from the development contact state shown in FIG. 5C to the development separation state shown in FIG. 5D. In addition, it becomes possible to reduce the relative difference of the movement member 31 between the front and back sides of the apparatus.

3) About FIGS. 7A to 7D

FIG. 7A is a partially enlarged view of the apparatus when seen from the front side during development contact, and

FIG. 7B is a partially enlarged view of FIG. 7A in which the relationship between the contact/separation means and the rib 4e of the development unit 4 is shown from the upper side of the apparatus. FIGS. 7C and 7D are views showing the relationship between the contact/separation means and the rib 4e of the development unit 4 like FIGS. 7A and 7B during development separation.

During the development contact, the rib 31f of the movement member 31 biases the rib 4e of the development unit 4 at two places in the direction of the front side of the apparatus as indicated by an arrow G in FIG. 7B with the elastic force of the pressure spring 32. Thus, the development roller 24 contacts the photosensitive drum 1.

On the other hand, during the development separation (standby state), the rib 31f of the movement member 31 separates from the rib 4e of the development unit 4 at two places in the front-back direction of the apparatus as indicated by an arrow J in FIG. 7D with the compression of the pressure spring 32. Thus, the development roller 24 separates from the photosensitive drum 1.

A description will be given, with reference to FIGS. 8A and 8B to FIG. 11, of the configuration of biasing and positioning the process cartridge with respect to the frame 102 with the opening and closing of the access door 101 serving as an opening/closing member.

1) About FIGS. 8A and 8B

FIGS. 8A and 8B are partially enlarged cross-sectional views showing the access door 101, the process cartridge 7, and the periphery of a guide rail 63 of the process cartridge 7 in a surface orthogonal to the horizontal surface (right-left direction). FIGS. 8A and 8B show the opening/closing operation of the access door 101 and the positional relationship of the process cartridge 7 or the like. FIGS. 8A and 8B are views of the apparatus when seen from the right side, FIG. 8A showing a state in which the access door 101 is put in a closed position where space, which is provided in the apparatus body and in which the process cartridge 7 is accommodated, is closed, FIG. 8B showing a state in which the access door 101 is put in an open position where the space for accommodating the process cartridge 7 is open in the apparatus body.

The frame 102 (FIG. 2) has a shaft 61 with its both ends rotatably supported, and an interlocking lever 60 is fixed to the shaft 61. The access door 101 has a rotation shaft 101b, and the rotation shaft 101b serves as the rotation supporting point of the access door 101. The access door 101 is provided with an engagement boss 101g, and the engagement boss 101g engages the interlocking lever 60 when the access door 101 changes from the closed state to the open state. Further, the shaft 61 rotates by a desired angle in a direction as indicated by a solid line in FIG. 8B with the opening of the access door 101.

2) About FIGS. 9A to 9C

FIGS. 9A and 9B are enlarged views of the front side of a K-station in a surface orthogonal to the horizontal surface (in the front-back direction of the apparatus), FIG. 9A showing a state in which the access door 101 is closed, FIG. 9B showing a state in which the access door 101 is open. FIG. 9C is a partially enlarged view of a shape in the vicinity of a drum guide portion 63h having only the rail 63.

A lower portion 5f of the drum unit 5 of the cartridge 7 is formed into a substantially T-shape and fitted in the drum guide portion 63h having a substantially U-shaped cross section as indicated by broken lines in FIG. 9C. Further, the upper portion of the drum unit 5 has an arc shape at its supporting portion that supports both ends of the photosensitive drum 1, and the arc shape is positioned with respect to

11

a V-shape **103e** of an upper frame. The biasing of the V-shape **103e** is performed by a pressing member **64** (**64a**, **64b**, **64c**, **64d**) arranged inside guide rail **63** (**63a**, **63b**, **63c**, **63d**). Thus, the process cartridge **7** is biased to the upper side of the apparatus when the access door **101** is closed. For the development unit **4**, a rib **4h** of the development frame **4f** is fitted in a development guide portion **63g** of the substantially U-shaped groove of the guide rail **63**, and an upper arc shape **4k** of the development frame **4f** is positioned with respect to the V-shape **103f** of the upper frame.

In the embodiment, in order to save the space of the apparatus and secure the rigidity of the guide rail **63** itself, the guide rail **63** is so configured that the drum guide portion **63h** and the development guide portion **63g** are integrally formed. In the image forming apparatus, the cartridges **7** (**7a**, **7b**, **7c**, **7d**) corresponding to the respective colors yellow (Y), magenta (M), cyan (C), and black (K) are arranged one by one to be adjacent to each other. Each of the cartridges **7** has the drum unit **5** having the photosensitive drum **1** and the development unit **4** having a container (first container) in which a developer is accommodated besides the development roller **24** that develops, with the developer, an electrostatic latent image formed on the photosensitive drum **1** of the drum unit **5**. In the guide rail **63** of the embodiment, the drum guide portion **63h** that guides the drum unit **5** of one of adjacent two cartridges **7** and the development guide portion **63g** that guides the development unit **4** of the other cartridge **7** are integrated with each other. However, the shape of the guide rail **63** is not limited to this, and the guide rail **63** may be replaced by a rail member in which the drum guide portion **63h** and the development guide portion **63g** are separated from each other.

A drum guide portion (first guide portion) **63h** of the guide rail **63** is provided at a position higher than that of the development guide portion (second guide portion) **63g**. Thus, since the drum unit **5** may be downsized in its height direction, a reduction in the storage space of user's replacement units is achieved. In addition, since the development unit **4** may be upsized in its height direction compared with the drum unit **5**, an increase in the capacity of contained toner is made possible.

When the access door **101** is open, the biasing of the cartridge to the V-shapes **103e** and **103f** is released. Thus, it becomes possible to extract the cartridge **7** from the apparatus body in the development separation state while reducing an operating force.

3) About FIGS. 10A and 10B

FIGS. 10A and 10B are schematic views showing the relationship between the guide rail **63** and the access door **101** in a surface orthogonal to the horizontal surface (in the right-left direction of the apparatus). FIG. 10A shows a state in which the access door **101** is open, and FIG. 10B shows a state in which the access door **101** is closed.

The guide rail **63** has pressing member accommodation portions **63e** at two places in the front-back direction of the apparatus. Biasing members (compression springs) **67** are provided between the pressing member accommodation portions **63e** and pressing members **64**, and the pressing members **64** are configured to bias the cartridge **7** to the upper side of the apparatus with respect to the guide rail **63**.

Further, the guide rail **63** is connected to the shaft **61** via a rail arm **65** (**65a**, **65b**, **65c**, **65d**), and connected to a frame not shown via a rail arm **66** on the rear side of the apparatus to form a four-joint parallel link as a link mechanism. Further, a tensile spring not shown is provided between the guide rail **63** and the frame, and the guide rail **63** is biased so as to change from a state shown in FIG. 10B to a state

12

shown in FIG. 10A. Thus, it becomes possible to elevate and bias the guide rail **63** and the process cartridge **7** with the opening/closing operation of the access door **101**.

4) About FIG. 11

FIG. 11 is a partially perspective view showing the configurations of guide rails **63c** and **63d** corresponding to cyan (C) and black (K), respectively, and the shaft **61**. As described above, a pressing member **68d** that presses the rib **4h** of the development frame **4f** is provided on the guide rail **63c** with respect to the development unit **4**. The pressing member **68d** is biased to the upper side of the apparatus by biasing members (compression springs) like the pressing member **64** for the drum unit **5** (see FIGS. 10A and 10B).

Slope Member

A description will be given, with reference to FIG. 11 and FIGS. 12A and 12B, of the configuration of a slope member **69** in the embodiment. FIGS. 12A and 12B are partially cross-sectional views of the vicinity of the slope member **69** in a surface orthogonal to the right-left direction of the apparatus, FIG. 12A showing a state in which the access door **101** is closed, FIG. 12B showing a state in which the access door **101** is open.

The slope member **69** is coupled to the guide rail **63** (**63a** to **63d**), the frame **102** of the apparatus body via the guide rail **63**, and the access door **101**. The slope member **69** has an engagement hole **69d** engaging an engagement boss **63f** provided on the guide rail **63**, and is rotatably supported about the engagement hole **69d** with respect to the guide rail **63**. In addition, the slope member **69** has an engagement groove **69e** engaging an engagement boss **101h** provided on the access door **101** with respect to the access door **101**, and is supported so as to be capable of changing its posture with respect to the access door **101** when the engagement boss **101h** slides inside the engagement groove **69e**. That is, the slope member **69** is configured to be capable of changing its posture with respect to the access door **101** so as to shift its connecting position with the access door **101** while changing its angle with respect to the access door **101**. Moreover, the access door **101** and the apparatus body are capable of accommodating the slope member **69** in space in which the process cartridge **7** is accommodated. The slope member **69** changes its posture with respect to the access door **101** so as to be accommodated in the above space while reducing its angle with respect to the access door **101** when the access door **101** moves from an open position to a closed position. Thus, when the access door **101** is put in the closed position, the slope member **69** is positioned inside the access door **101** in the inserting/extrating direction of the unit.

As shown in FIG. 12A, the slope member **69** is stored so as to get into the inside (accommodation portion) of the access door **101** when the access door **101** is closed. Therefore, it is possible to arrange the slope member **69** in small space without increasing a product size in the front direction of the apparatus. Further, as shown in FIG. 11 and FIG. 12B, the slope member **69** protrudes in the front direction of the apparatus together with the access door **101** when the access door **101** is open. Further, the access door **101** is provided with a guide portion **101i** serving as a third guide portion. Outside the space of the apparatus body in which the process cartridge **7** is accommodated, the guide portion **101i** guides the unit in the inserting/extrating direction at a position lower than that of the guide rail **63** serving as the first guide portion in a height direction orthogonal to the inserting/extrating direction of the unit.

The slope member **69** has, on its upper surface, a flat surface portion **69a** serving as an end on a side close to the first guide portion (on a downstream side in an attachment

direction) and an inclined surface portion 69b. The inclined surface portion 69b guides the unit in a direction inclined with respect to the inserting/extracting direction (horizontal direction) of the unit. The flat surface portion 69a has substantially the same height as that of the drum guide portion 63h of the guide rail 63. The height of the inclined surface portion 69b at one end (upstream side) on the front side of the apparatus is lower than that of the guide portion 101i provided on the access door 101. The other end (downstream side) of the inclined surface portion 69b is smoothly connected to the flat surface portion 69a. Thus, the slope member 69 is, when the access door 101 is put in the open position, capable of guiding the drum unit 5 to the development guide portion 63g provided at a position higher than that of the drum guide portion 63h in the height direction orthogonal to the inserting/extracting direction. Note that the flat surface portion may be provided at an end on a side close to the second guide portion. Walls are provided on both ends of the guide portion 101i, the inclined surface portion 69b, and the flat surface portion 69a, and the width between the walls is substantially the same as that of the lower portion 5f of the drum unit 5 (5a, 5b, 5c, 5d). Here, the position of the slope member 69 in the right-left direction of the apparatus when seen from the front side of the apparatus is substantially below the gravity position of the drum unit 5. Therefore, the drum unit 5 is prevented from falling down in the right-left direction of the apparatus when the drum unit 5 is inserted.

When inserting the drum unit 5 in the apparatus body, a user picks up the handle portion 5e and puts the tip end in the inserting direction of the lower portion 5f in the guide portion 101i and then causes the lower portion 5f to pass through the guide portion 101i, the inclined surface portion 69b, the flat surface portion 69a, and the drum guide portion 63h in this order. Therefore, since the drum unit 5 is inserted from a lower position compared with a state in which the photosensitive drum 1 (1a to 1d) is attached inside the apparatus, it becomes possible to attach the drum unit 5 without damaging the surface of the photosensitive drum 1.

When extracting the drum unit 5 attached to the apparatus body, the user picks up the handle portion 5e and then causes the lower portion 5f to pass through the drum guide portion 63h, the flat surface portion 69a, the inclined surface portion 69b, and the guide portion 101i in this order. At this time, since the drum guide portion 63h and the guide portion 101i have a flat surface, it becomes possible to prevent the drum unit 5 from being extracted with a great force and extract the drum unit 5 while preventing the same from coming off.

The inclined surface portion 69b is provided with an arrow-shaped engraved mark serving as an insertion instructing portion (display portion) 69c. By inserting the drum unit 5 in a direction as indicated by the insertion instructing portion 69c, it becomes possible for the user to perform the smooth insertion of the drum unit 5.

According to the embodiment, it is possible to prevent the occurrence of damage such as a scratch on the surface of a photosensitive drum during the insertion of a cartridge and achieve an improvement in usability and maintenance while reducing the upsize of a product and an increase in the costs of the process cartridge.

The access door 101 needs to support its weight as a guide when the cartridge 7 (7a to 7d) is inserted/extracted. In the embodiment, each of the plurality of slope members 69 is supported by the engagement boss 63f and the engagement boss 101h. Therefore, the single access door 101 is configured to be suspended and reinforced by the four slope members 69 with respect to the frame 102 of the apparatus

body. Therefore, it becomes possible to support the weight of the cartridge 7 without additionally providing a suspending member even if the strength of the access door 101 is low.

5 Modified Example of Embodiment

In the embodiment, the insertion instructing portion 69c of the slope member 69 is the arrow-shaped engraved mark that instructs the inserting direction. However, a label, print, or the like may be used instead of the arrow-shaped engraved mark, and a display portion that displays an extracting direction instead of the inserting direction may be used. In addition, instead of the arrow-shape engraved mark, characters or shapes such as "DRUM" indicating the drum unit 5, color information such as YMCK, the station numbers of cartridges, or the like may be expressed or described in combination. That is, a display portion that displays a unit to be guided may be provided. In order to differentiate the slope member 69 from the access door 101 and make the inserting/extracting guide of the drum unit 5 conspicuous for the user, the component colors of the access door 101 and the slope member 69 may be different from each other. Although the same components are commonly used in the four slope members 69 to improve costs and assembling performance, other components may be used to realize these purposes.

In addition, in the embodiment, the cartridge 7 divided into the two bodies of the development unit 4 and the drum unit 5 is used to reduce the storage space for user's replacement units with the commonization of the drum unit 5 between the four stations. However, the cartridge 7 may have other shapes. For example, the cartridge 7 in which the development unit 4 and the drum unit 5 are constituted by one body may be used. In this case, the guide portion 101i of the access door 101, the flat surface portion 69a of the slope member 69, the inclined surface portion 69b, and the drum guide portion 63h of the guide rail 63 may guide the insertion/extraction of the cartridge 7.

In the embodiment, the access door 101 that opens/closes the opening portion of the apparatus body serves also as the exterior of the apparatus body. However, with an exterior door additionally provided, the access door 101 may serve as a door inside the apparatus body. In this case, the slope member 69 may be configured to operate with the opening/closing of the access door 101 inside the apparatus body.

45 Second Embodiment

Next, a description will be given of a second embodiment of the present invention. The first embodiment provides the configuration having the guide rail 63 having the guide portions different in height when the access door 101 is open, the configuration having the slope member 69 that couples the guide portion 101i of the access door 101 and the drum guide portion 63h of the guide rail 63 to each other. However, the configuration may not have the slope member 69. Hereinafter, a description will be given of the second embodiment that does not have the slope member 69. Note that in the second embodiment, the same configurations as those of the first embodiment such as the entire configuration of an image forming apparatus will be denoted by the same symbols and their descriptions will be omitted.

60 A description will be given, with reference to FIGS. 13 and 14, of the configuration of a guide rail 63 according to the second embodiment. In the embodiment, a drum guide portion 63h of the guide rail 63 is provided at a position higher than that of a development guide portion 63g in a vertical direction like the first embodiment. That is, the drum guide portion 63h corresponding to a drum unit 5 and a development guide portion 63g corresponding to a devel-

15

opment unit **4** are provided at different heights in the vertical direction. Thus, a user is allowed to avoid mixing up the drum unit **5**, the development unit **4**, and the guide portions corresponding to the drum unit **5** and the development unit **4** and erroneously attaching the drum unit **5** and the development unit **4**. As a result, damage on the surface of a photosensitive drum and the surface of a development roller may be prevented during the insertion of a cartridge. Further, according to the configuration of the embodiment, storage space for replacement units may be reduced since the drum unit **5** is downsized in its height direction. In addition, since the development unit **4** may be upsized in its height direction compared with the drum unit **5**, it is possible to achieve an increase in the capacity of toner in a development container.

Note that in the embodiment, an inclined portion is provided at an upstream-side end in the inserting direction of the drum guide portion **63h** instead of the slope member **69** of the first embodiment. The inclined portion is provided so as to be inclined to move upward from below the apparatus body from an upstream side to a downstream side in the inserting direction. Thus, the configuration is made simpler, and the drum unit **5** placed on a guide portion **101i** may be stably smoothly inserted in the drum guide portion **63h**.

While the present invention has been described with reference to exemplary embodiments, it is to be understood that the invention is not limited to the disclosed exemplary embodiments. The scope of the following claims is to be accorded the broadest interpretation so as to encompass all such modifications and equivalent structures and functions.

This application claims the benefit of Japanese Patent Application No. 2016-214489, filed on Nov. 1, 2016, and Japanese Patent Application No. 2017-179418, filed on Sep. 19, 2017, which are hereby incorporated by reference herein in their entirety.

What is claimed is:

1. An image forming apparatus, comprising:
a drum cartridge that includes a photosensitive drum configured to bear a toner image and to be rotatable about a rotational axis;
a developing cartridge that includes a developing roller configured to supply toner to the photosensitive drum; and
an apparatus main body to which the drum cartridge and the developing cartridge are independently and detachably mountable in a direction of the rotational axis, the apparatus main body including:
an opening through which the drum cartridge and the developing cartridge pass when being mounted to the apparatus main body;
a cover configured to move between an open position where the cover does not cover the opening and a closed position where the cover covers the opening;
a first guide configured to guide the drum cartridge and to support the drum cartridge from below, the first guide extending in the direction of the rotational axis;
a second guide configured to guide the developing cartridge and to support the developing cartridge from below, the second guide extending in the direction of the rotational axis and being arranged at a position lower than that of the first guide, the second guide overlapping with the first guide when viewed in a direction orthogonal to the rotational axis; and
a slope guide configured to guide the drum cartridge toward the first guide and to support the drum cartridge from below, the slope guide having a slope upwardly inclined toward the first guide.

16

2. The image forming apparatus according to claim 1, wherein the cover includes a third guide configured to guide the drum cartridge toward the slope guide and to support the drum cartridge from below when the cover is in the open position, the third guide being arranged at a position lower than that of the first guide.

3. The image forming apparatus according to claim 2, wherein the slope of the slope guide is upwardly inclined from a position lower than the third guide.

4. The image forming apparatus according to claim 1, wherein the apparatus main body includes an intermediate transfer unit to which the toner image is transferred from the photosensitive drum, and

wherein the drum cartridge and the developing cartridge are arranged at positions lower than that of the intermediate transfer unit.

5. The image forming apparatus according to claim 1, wherein the slope guide includes first and second engaging portions engaging with a first engaged portion of the first guide and a second engaged portion of the cover, respectively.

6. The image forming apparatus according to claim 5, wherein an engaging position between the second engaging portion of the slope guide and the second engaged portion of the cover is capable of shifting in conjunction with a movement of the cover from the open position to the closed position, so that a posture of the slope guide with respect to the cover in a case where the cover is in the closed position is different from that in a case where the cover is in the open position, for accommodating the slope guide inside the apparatus main body when the cover is in the closed position.

7. The image forming apparatus according to claim 1, wherein the slope guide includes a flat surface downstream of the slope in a direction in which the drum cartridge is mounted to the apparatus main body, the flat surface being arranged at the same height as the first guide.

8. An image forming apparatus, comprising:
a cartridge that includes a rotating member rotatable about a rotational axis;
an apparatus main body to which the cartridge is detachably mountable in a direction of the rotational axis, the apparatus main body including:
an opening through which the cartridge passes when being mounted to the apparatus main body;
a cover configured to move between an open position where the cover does not cover the opening and a closed position where the cover covers the opening;
a first guide configured to guide the cartridge and to support the cartridge from below, the first guide extending in the direction of the rotational axis; and
a slope guide configured to guide the cartridge toward the first guide and to support the cartridge from below, the slope guide having a slope upwardly inclined toward the first guide,
wherein the cover includes a second guide configured to guide the cartridge toward the slope guide and to support the cartridge from below when the cover is in the open position, the second guide being arranged at a position lower than that of the first guide.

9. The image forming apparatus according to claim 8, wherein the slope of the slope guide is upwardly inclined from a position lower than the second guide.

10. The image forming apparatus according to claim 8, wherein the slope guide includes first and second engaging

portions engaging with a first engaged portion of the first guide and a second engaged portion of the cover, respectively.

11. The image forming apparatus according to claim 10, wherein an engaging position between the second engaging portion of the slope guide and the second engaged portion of the cover is capable of shifting in conjunction with a movement of the cover from the open position to the closed position, so that a posture of the slope guide with respect to the cover in a case where the cover is in the closed position is different from that in a case where the cover is in the open position, for accommodating the slope guide inside the apparatus main body when the cover is in the closed position. 5 10
